UNITED STATES PATENT OFFICE.

WILLIAM M. MITCHELL, OF LOUISVILLE, KENTUCKY.

RAIL-ANCHOR.

1,184,479.

Specification of Letters Patent. Patented May 23, 1916.

Application filed March 6, 1916. Serial No. 82,475.

To all whom it may concern:

Be it known that I, WILLIAM M. MITCHELL, a citizen of the United States, residing in Louisville, county of Jefferson, and State of Kentucky, have invented certain new and useful Improvements in Rail-Anchors, of which I do declare the following to be a full, clear, and exact description, reference being had to the accompanying drawing, 10 forming a part of this specification.

The invention consists in the novel features of construction hereinafter described, illustrated in the accompanying drawing and particularly pointed out in the claims 15 at the end of this specification.

Figure 1 is a plan view showing a rail anchor embodying my invention and showing said anchor applied to a railway rail. Fig. 2 is a side view of my improved anchor, the lower portion of the railway rail 20 being shown in vertical section. Fig. 3 is a view in vertical section on line 3—3 of Fig. 2, the rail base being omitted. Fig. 4 is an inverted plan view of the locking jaw 25 of my anchor. Fig. 5 is a plan view of the end portion of the anchor on which the locking jaw is mounted.

The body portion A of my improved rail anchor is adapted to extend beneath the 30 base of the railway rail B and bear against the under side of said rail base; and at one end the rail anchor is provided with a jaw A' preferably formed integral with the body portion and provided with a groove 35 to receive the base flange b of the rail. At its opposite end, the body portion A of the rail anchor is depressed or extended downwardly and outwardly and is provided with a depending abutment A² adapted to bear 40 against the railway tie C, as shown in Fig. 3 of the drawings. On the upper surface of the downwardly and outwardly extended end portion of the rail anchor is formed a raised rib A³ having an expanded head a, 45 this rib being adapted to enter a downwardly facing groove d that is formed in the under side of a locking jaw D, the groove d of this locking jaw corresponding in outline to the shape of the rib A³. Upon the upper face of the depressed and outwardly extended portion of the rail anchor are formed teeth or serrations a², preferably on both sides of the rib A³, as clearly shown in Fig.

5, although the provision of these teeth or serrations a² upon both sides of the rib is 55 not essential. So, also, the lower surface

of the locking jaw D is formed with teeth or serrations d' adapted to engage and interlock with the teeth a².

The inner portion of the locking jaw D 60 is provided with a groove d² adapted to engage the base flange b' of the rail B. The rib A³ is inclined inwardly and downwardly toward the abutment A² so that as the locking jaw D is moved toward the abutment 65 and into position for use, it will be caused to securely engage and hold the base flange b' of the rail B; and the relative dimensions of the rib A³ and the groove in the locking jaw D will be such that as the locking jaw is first applied to the rib, the teeth d' of the locking jaw will ride over the teeth a² until the locking jaw firmly engages the base flange b' of the rail B, when the interlocking of the teeth d' and a² will 70 securely hold the locking jaw D against danger of accidental movement. It will be noticed that considerable space is formed between the lower inclined face d⁴ of the locking jaw D and the face a⁴ of the body 75 portion A of the anchor, this space allowing a free clearance for dirt, etc., and inasmuch as the groove in the jaw D faces downwardly, all danger of accumulation of dirt or water in the groove of the locking jaw 80 will be avoided. This is a feature of importance, as any accumulation of dirt, cinders, or the like, between the locking jaw and the anchor would tend, under the constant jars to which the anchor is subjected, 85 to wear away the parts and endanger the loosening of the locking jaw.

The precise details of construction above set out may be varied without departure 90 from the spirit of the invention.

Having thus described my invention, what I claim as new and desire to secure by Letters Patent is:

1. A rail anchor comprising a body portion having at one end a jaw to engage the 100 base flanges of a rail and having at its opposite end a downwardly and outwardly extending portion provided with a raised rib at a distance from its end, and a locking jaw provided upon its under side with a 105 downwardly facing groove to engage said rib and having an outwardly projecting part to bear upon the upper surface of the anchor outside of said rib.

2. A rail anchor comprising a body portion having at one end a jaw to engage one 110 of the base flanges of a rail and having

at its opposite end a depressed portion provided with teeth or serrations and with a raised rib, and a locking jaw provided upon its under side with a groove to engage said rib and with teeth or serrations to interlock with the teeth or serrations on the anchor.

3. A rail anchor comprising a body portion having at one end a jaw to engage one of the base flanges of a rail and having at its opposite end a depressed portion and provided with a raised rib extending diagonally across said depressed portion, and a locking jaw provided on its under side with a diagonal groove to engage said rib, said rib and said groove being inclined toward the body portion of the anchor.

4. A rail anchor comprising a body portion having at one end a jaw to engage one of the base flanges of a rail and having at its opposite end a depressed portion and provided with a raised rib extending transversely of said depressed portion and having an expanded head and a locking jaw provided upon its under side with an expanded groove to receive said rib, said locking jaw being provided upon its inner side with a groove to receive the rail flange and with a part extending downwardly from said groove to the depressed part of said body portion.

WILLIAM M. MITCHELL
